UNITED STATES PATENT OFFICE.

LIONEL MANUEL HENDLER, OF BALTIMORE, MARYLAND.

DESIGN FOR A VEHICLE BODY.

Application filed July 24, 1925. Serial No. 14,204. Term of patent 14 years.

To all whom it may concern:

Be it known that I, LIONEL MANUEL HENDLER, a citizen of the United States, residing at Baltimore, in the State of Maryland, have invented a new, original, and ornamental Design for Vehicle Bodies, of which the following is a specification, reference being had to the accompanying drawing, forming part thereof, in which:

Fig. 1 is a side elevation of the vehicle body showing my new design; and,
Fig. 2 is a rear elevation of the same.

What I claim is:

The ornamental design for a vehicle body, substantially as shown.

LIONEL MANUEL HENDLER.
